[57] CLAIM

The ornamental design for a door frame extrusion, as shown and described.

DESCRIPTION

FIG. 1 is a fragmentary perspective view of the door frame extrusion of the present invention;

FIG. 2 is a fragmentary elevation view of the left end of the door frame extrusion in FIG. 1. The right end of the extrusion is not separately illustrated because it is merely a reverse or mirror image of the left end;

FIG. 3 is a fragmentary front elevation view of the door frame extrusion in FIG. 1;

FIG. 4 is a fragmentary back elevation view of the door frame extrusion in FIG. 1;

FIG. 5 is a fragmentary top view of the door frame extrusion in FIG. 1; and,

FIG. 6 is a fragmentary view of the bottom of the door frame extrusion in FIG. 1.

The door frame extrusion has been broken on the end as an indication of indeterminate length.
